UNITED STATES PATENT OFFICE

135,831

DESIGN FOR A HOLDER FOR INKWELLS AND PENS

William M. Gallagher, Oklahoma City, Okla.

Application March 30, 1943, Serial No. 109,861

Term of patent 14 years

To all whom it may concern:

Be it known that I, William M. Gallagher, a citizen of the United States and a resident of Oklahoma City, in the county of Oklahoma and State of Oklahoma, have invented the new, original, and ornamental Design for a Holder for Inkwells and Pens, of which the following is a specification.

Reference is had to the accompanying drawing, forming part thereof, in which:

Fig. 1 is a top plan view of a holder for inkwells and pens, showing my new design;

Fig. 2 is a side elevational view thereof;

Fig. 3 is a longitudinal central sectional view thereof.

I claim:

The ornamental design for a holder for inkwells and pens, as shown.

WILLIAM M. GALLAGHER.
